United States Patent Office.

S. D. ENGLE, OF HAZLETON, PENNSYLVANIA.

Letters Patent No. 98,677, dated January 11, 1870.

IMPROVEMENT IN DUST-RINGS FOR WATCH-FRAMES.

The Schedule referred to in these Letters Patent and making part of the same.

To all whom it may concern:

Be it known that I, S. D. ENGLE, of Hazleton, in the county of Luzerne, and State of Pennsylvania, have invented a new and useful Improvement in Watches; and I do hereby declare that the following is a full, clear, and exact description thereof, which will enable others skilled in the art to make and use the same, reference being had to the accompanying drawings, forming part of this specification.

This invention relates to a new and useful improvement in watches, whereby the movement of the watch is protected from harm by reason of dust; and

It consists in a protecting-ring or band around the watch-movement, and attached thereto, of the form and construction hereinafter more fully described.

In the accompanying drawing—

Figure 1 represents the back of the movement, showing the edge of the protecting-ring.

Figure 2 is a vertical cross-section on the line $z z$ of fig. 1.

Similar letters of reference indicate corresponding parts.

A is the protecting-ring, the upper edge of which closely fits the edge of the face B, as seen in fig. 2.

As also seen in this figure, the ring extends down and covers the entire space between the face and back

of the watch, thus perfectly screening the wheels and the entire movement from dust.

The form of the protecting-ring (in cross-section) is seen in fig. 2.

C and D are offsets between the face and back, so made that the ring may conform to the shape and perfectly protect the entire movement.

The ordinary case is used with this improvement, and is not made with especial reference thereto, only being of sufficient diameter to admit it.

The protecting-ring is struck up from very thin metal, and at a slight expense.

It is attached to the movement by means of a pin on one side, as seen at e, beneath the dial-plate, and by head of a screw on the back, as seen at f.

Having thus described my invention,

I claim as new, and desire to secure by Letters Patent—

A movement-protector for watches, consisting of the ring A, with offsets C D thereon, and attached to the movement by means of pin e, as shown and described.

S. D. ENGLE.
